US0D1061454S

(12) **United States Design Patent** (10) **Patent No.:** **US D1,061,454 S**
(45) **Date of Patent:** **** Feb. 11, 2025**

(54) **REMOTE CONTROL**

(71) Applicant: **Shantou Fengma Toy Industry Co., LTD**, Shantou (CN)

(72) Inventor: **Haibo Li**, Shantou (CN)

(73) Assignee: **Shantou Fengma Toy Industry Co., LTD**, Shantou (CN)

(**) Term: **15 Years**

(21) Appl. No.: **29/889,205**

(22) Filed: **Apr. 10, 2023**

(30) **Foreign Application Priority Data**

Feb. 17, 2023 (CN) 202330058205.5

(51) **LOC (15) Cl.** **13-03**

(52) **U.S. Cl.**

USPC **D13/168**; D21/333

(58) **Field of Classification Search**

(57) **CLAIM**

The ornamental design for a remote control, as shown and described.

DESCRIPTION

FIG. 1 is a first perspective view of a remote control showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the remote control that form no part of the claimed design.

1 Claim, 8 Drawing Sheets
